COMBINATION CLEANING TOOL

Stanley W. Fish, Springfield, Mass.

Application July 16, 1942, Serial No. 451,206

3 Claims. (Cl. 287—58)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a combination tool for a firearm, more particularly to a tool for cleaning the chamber of the firearm.

Adequate cleaning of the chamber of a firearm is usually a difficult procedure and is especially true of firearms having receivers of such shape as to obstruct free access to the bore. When the chamber is not readily accessible from the breech end, it is necessary to improvise some sort of cleaning implement for scouring the chamber, as a suitably formed offset cleaning rod. For military use such an improvised cleaning tool would be decidedly inconvenient to carry separately in the field. As it is imperative that a rifle bore and chamber be kept clean at all times, particularly the chamber, it is highly desirable to carry cleaning implements with the rifle. This is usually accomplished by inserting these implements in a suitable recess within the butt-stock of the firearm, access to this recess being made thru a trap door in the butt plate. Occasionally it is desirable to disassemble the entire rifle for a thorough cleaning and infrequently to replace a damaged or defective part. This procedure is facilitated by a screw-driver and a drift pin. A ruptured cartridge case in the chamber is best removed with a special extracting tool. If these various tools are carried separately some will undoubtedly be lost or misplaced and hence will not be available when most urgently needed. Therefore a tool which combines the several tools in one, which can be conveniently carried within the buttstock of the firearm, and is convenient to use, is very desirable.

Accordingly it is an object of this invention to provide a compact combination tool which combines implements for cleaning the chamber of the firearm and for disassembling the firearm.

A particular object of this invention is to provide a combination tool incorporating therein an extractor removing tool for removal of the extractor from the bolt of a rifle such as disclosed in U. S. Patent No. 1,892,141 to John C. Garand.

The specific nature of the invention as well as other objects and advantages thereof will clearly appear from a description of a preferred embodiment as shown in the accompanying drawing, in which:

Fig. 1 is a top elevational view of a combination tool shown partially in section.

Fig. 2 is a longitudinal sectional view taken along the central longitudinal axis of Fig. 1.

Fig. 3 is a cross sectional view taken along the plane 3—3 of Fig. 2 showing a preferred method

of securing the cleaning brush to the combination tool.

Fig. 4 is a partial bottom view of Fig. 2 taken opposite the plane 4—4 showing the ruptured cartridge case extractor groove.

Fig. 5 is a right end elevational view taken opposite the plane 5—5.

Referring to Fig. 1, there is shown in its preferred form a combination tool in assembled relation. A handle 1 is preferably formed from a cylindrical bar. One end of handle 1 has an integrally formed head 1a. Two fork-like prongs 2a and 2b (Fig. 5) project upwardly from the end of head 1a. These prongs are for removing the extractor from the bolt of a rifle such as disclosed in the aforementioned U. S. Patent No. 1,892,141. A suitable recess 3 is provided on the head 1a between the prongs 2a and 2b to hold an ejector (not shown) in position while assembling or disassembling an extractor (not shown). Onto the face 1b of the head 1a, near the lower edge of the face and opposite the prongs 2a and 2b, a narrow milled slot 4 (Fig. 4) is provided. This slot is semi-circular in depth and fits the base of a cartridge. The lower side 1c of head 1a opposite the prongs 2a and 2b is milled flat and a semi-circular opening 5 (Fig. 4) smaller in diameter than the slot 4 in order to fit the extractor groove of a cartridge case, is provided from the flat side 1c to the slot 4. Just to the rear of the surface 1c a clearance cut 6 is provided in the head 1a to allow the tool to be inserted within the receiver (not shown) of a rifle similar to that shown in U. S. Patent No. 1,892,141 to engage and extract a ruptured cartridge case.

Adjacent the head 1a two flat milled surfaces 7a and 7b (Fig. 2) diametrically opposed, are provided on the handle 1. These surfaces are in the same horizontal plane as the slot 4. A centrally located transverse hole 8 is provided in the handle 1 approximately in the center of the surfaces 7a and 7b. A rivet 9 inserted in the hole 8 fastens a blade 10 securely but movably about the axis of the rivet 9 to the handle 1. The blade 10 has a flat outwardly projecting boss 10a which bears against the surface 7b. One end 10a of blade 10 is shaped to form a conventional screw-driver blade while the other end 10b forms a conventional drift pin. The blade 10 snugly rests against the handle 1 when the blade is brought parallel to the handle.

A longitudinal hole 11 is provided within the other end of the handle 1, into which is inserted a chamber brush extension rod 12. The extension rod 12 has an integrally formed short tubular head 12a projecting outwardly from the handle 1. Two displaced holes 13a and 13b are provided in the rod 12 and are connected by a slot 14. A spring clip 15 slidably surrounds the handle 1.

The clip 15 has an integral spring arm 15a extending along the handle 1, the end of which is slightly upturned. A pin 16 having an integral shoulder 16a is riveted or otherwise secured to the arm 15a and projects downwardly thru a hole 17 (Fig. 2) in the handle 1 into the hole 13a in the rod 12. A detent 15b provided on the clip 15 engages a corresponding notch 18 in the handle 1 after the pin 16 has been inserted in the hole 17 and the clip 15 pushed slightly to the rear so that the smaller diameter of pin 16 engages the rear edge of hole 17. Thus when the upturned end of the spring arm 15a is lifted upwardly the shoulder 16a on pin 16 will bear against the underside of the handle 1 thereby preventing the spring arm from being pulled out of the interior of handle 1. Thus, accidental disassembly of the rod 12 from the handle 1 can not occur during the change in positioning of the rod from its extended to its collapsed position with respect to the handle, or vice versa. For intentional disassembly of the rod 12 from the handle 1, the spring clip 15 must be pushed slightly forward against the spring force exerted by detent 15b to a position where the shoulder 16a is aligned with the hole 17 in the handle 1. A suitable cleaning brush 19 is movably secured to the end 12a of the rod 12 by a pin 20 which is inserted in suitable holes 21 and 22 in the end 12a and thru the hole 19a of the brush 19. The pin 20 is secured to the end 12a by the ring spring 23 which surrounds the member 12a. The spring 23 is secured to the pin 20 by any suitable means, as by riveting. The hole 19a thru the end 19b of brush 19 is cone shaped at each end to permit angular motion of the brush 19. While the brush 19 is preferably attached to the U-shaped member in the manner shown, the brush may be attached to this member by any suitable conventional toggle or universal joint means.

To use the combination tool for cleaning the chamber of a rifle the extension rod 12 is first extended by lifting the pin 16 out of the hole 13a by raising the spring 15a and withdrawing rod 12 from the hole 11 until the pin 16 strikes a shoulder 13c on rod 12 at the rear of hole 13b. The pin 16 is then allowed to enter the hole 13b thereby locking the rod 12 to the handle 1. With the tool thus extended the brush 19 is readily inserted into the cleared chamber of a firearm. As the brush 19 is attached to the handle 1 by a toggle joint the handle can be bent at a considerable angle to clear any obstructing portion of the receiver. For the best scouring action the handle should be revolved, such revolving motion being imparted to the brush by the toggle joint even though the handle may not be parallel to the chamber. The tool is most conveniently rotated when the blade 10 is pivoted to a transverse position with respect to the body of the tool. The blade 10 in such position facilitates grasping of the tool and permits a ready application of a revolving motion.

A ruptured cartridge case may be extracted from the chamber after the bolt is withdrawn by holding the tool in a vertical position and sliding the head 1a of the tool over the head of a cartridge (not shown) so that the slot 4 engages the rim of the cartridge. Using the bridge of a receiver (not shown) as a fulcrum and the handle 1 as a lever the ruptured case is readily removed when pressure is exerted against the handle. The screwdriver 10a and drift pin 10b may be used in a conventional manner, the han-

dle 1 also serving as a handle for the screwdriver when the blade 10 is turned at an angle to the handle, about the pin 9.

The extension rod 12 of this tool is provided to give extra length to the tool so that when used for cleaning the chamber of a rifle the handle 1 will project beyond the breech mechanism (not shown), thereby eliminating the danger of injury to the user by keeping the hand away from contact with any metal projections of the breech.

The combination tool is however conveniently carried within a suitable recess in the buttstock of a rifle (not shown) when the rod 12 is in the fully inserted position as shown in Fig. 2 and the blade 10 is turned parallel to the handle 1. Thus the tool becomes a compact combination of useful cleaning and disassembly implements which are not easily lost and which may be carried with the rifle with no inconvenience and be ready for use at all times.

I claim:

1. In a collapsible tool having a tubular body and a working member slidably mounted therein, the improvement comprising a plunger member arranged to be insertable thru a hole in said body portion, said plunger member having two spaced enlarged portions, a plurality of recesses spaced along the length of said working member constructed to be engaged by the inserted end of said plunger, means securing said plunger to said body in an off-center relationship to said hole wherein said spaced enlarged portions overlap opposite sides of the wall of said body portion, said last mentioned means arranged to resiliently bias said plunger into engagement in any desired recess.

2. In a collapsible tool having a tubular body and a working member slidably mounted therein, the improvement comprising a spring clip secured to said body, a plunger secured to said clip and arranged to be insertable through a hole in said body, an enlarged portion on the inserted end of said plunger, said clip constructed to resiliently hold said plunger in an inserted off-center position in said hole, whereby said enlarged portion overlaps a portion of the inside wall of said body adjacent said hole, and a plurality of recesses spaced along the length of said working member and constructed to be engaged by the inserted end of said plunger.

3. In a collapsible tool having a tubular body and a working member slidably mounted therein, the improvement comprising a retaining clip having a cylindrical portion constructed to surround said tubular body and a leaf spring portion constructed to lie along the surface of said tubular body in an axial direction, a plunger secured to said leaf spring portion and arranged to be insertable thru a hole in said tubular body, an enlarged portion on the inserted end of said plunger, a detent on the cylindrical portion of said retaining clip arranged to cooperate with a notch on said tubular body whereby said retaining clip may be resiliently secured to said body at a position where said enlarged portion of said plunger overlaps a portion of the inside wall of said body adjacent said hole, a plurality of recesses spaced along the length of said working member and constructed to be engaged by the inserted end of said plunger, said leaf spring portion arranged to resiliently bias said plunger into engagement in any desired recess.
